UNITED STATES PATENT OFFICE.

DAVID WILSON, OF KANSAS CITY, MISSOURI.

EARTH-AUGER.

1,074,304.

Specification of Letters Patent. Patented Sept. 30, 1913.

Application filed April 29, 1912. Serial No. 693,794.

To all whom it may concern:

Be it known that I, DAVID WILSON, a citizen of the United States, and a resident of Kansas City, in the county of Jackson 5 and State of Missouri, have invented certain new and useful Improvements in Earth-Augers, of which the following is a specification.

My invention relates to improvements in 10 earth augers.

It relates particularly to the type of earth augers in which two conveyer belts are disposed at opposite sides of and follow a drill shaft.

15 One object of my invention is to provide a simple, durable and efficient construction which will permit the excavated dirt to be dumped into a single chute at one side of the machine.

20 A further object of my invention is to provide a novel construction in which the two conveyer belts will occupy a minimum of space transversely relatively to the circle cut by the bit attached to the drill shaft.

25 Other novel features of my invention are hereinafter fully described and claimed.

In the accompanying drawings which illustrate the preferred form of my invention, Figure 1 is a side elevation of a machine 30 provided with my invention. Fig. 2 is a front elevation of the same, with the discharge chute removed. Fig. 3 is a plan view of the guide frame and parts connected therewith. Fig. 4 is a horizontal section on the line *a*—*b* of Fig. 6. Fig. 5 is an elevation of the lower part of the auger, showing it in operative position, a well lining section being shown in vertical section.

35 Fig. 6 is a vertical section on the line *c*—*d* of Fig. 3. Fig. 7 is a vertical section on the line *e*—*f* of Fig. 3.

Similar reference characters designate similar parts in the different views.

1 designates a truck having mounted mov- 45 ably thereon a platform 2 to the forward end of which is secured the lower ends of two vertical guide posts, 3, the upper ends of which are connected by a cross beam 4. Vertically slidably mounted between the

50 posts 3 is a slidable head 5 in which is rotatively mounted a drill shaft 6 to the lower end of which is secured a bit 7 of any suitable type.

At opposite sides of the drill shaft 6 are 55 rotatively mounted in the head 5 two horizontal sectional shafts 8, the axes of which

are preferably disposed in a vertical plane which bisects longitudinally the drill shaft 6.

Secured respectively to the shafts 8 are two sprockets 9 which respectively drive 60 two vertical conveyer belts 10 provided with buckets 11, and the lower ends of which belts are respectively mounted on sprockets 12 rotatively mounted on horizontal pins 13 mounted at opposite sides of the drill shaft 6 in a block 14 secured to the lower end of a vertical tube 15 in which the drill shaft is rotatable, and which has its upper end secured by a sleeve 16 to a removable portion 17 of the head 5.

70 The upper end of the drill shaft 6 is square and fitted in a square socket in the lower end of a vertical shaft 18 which is rotatively mounted in the head 5 and has secured to it a spur gear wheel 19 which meshes with a pinion 20 longitudinally movable on a vertical shaft 21 the upper end of which is rotatively mounted in a bracket 22 secured to the cross beam 4 and the lower end of which is stepped in a block 23 se- 75

cured to the platform 2. The pinion 20 has a feather 24 which is slidable in a vertical groove 25 provided in the shaft 21. A spur gear wheel 26 is similarly secured on the shaft 21 and meshes with the spur teeth on 80 the periphery of a gear wheel 27 which is rotative on the shaft 18 and is provided with internal teeth which mesh with a pinion 28 secured to a vertical shaft 29 to which is secured a bevel gear wheel 30, 85 which meshes with another bevel gear wheel 31 secured to one of the horizontal shafts 8. The other shaft 8 has secured to it a bevel gear wheel 32 which meshes with a bevel gear wheel 33 secured to a vertical shaft 34, 90 to which is secured a pinion 35 which meshes with the spur or external teeth of the gear wheel 27. The shafts 29 and 34 are rotatively mounted in the head 5.

When the shaft 21 is rotated the drill 100 shaft 6 is rotated by means of the pinion 20, gear wheel 19 and shaft 18, and the two conveyer belts are driven in like direction by means of the sprockets 9, shafts 8, bevel gear wheels 31, 32, 30 and 33, shafts 29 and 24, pinions 28 and 35, and gear wheels 27 and 26 just described.

Any suitable means may be employed for rotating the shaft 21 as, for example an engine 36 mounted on the platform 2 and 110 having suitable driving mechanism connecting it with the shaft 21.

Suitable means may be employed for vertically moving the head 5 when the drill is turned and the conveyer belts are driven, as, for example, suitable mechanism connecting said head with the engine 36.

In an application filed by me on February 4, 1911, Serial Number 606,573, I have fully described the mechanism for driving the shaft 21 from the engine 36, and for raising and lowering the head 5 by mechanism operated by the engine 36.

In the operation of my invention, as the drill shaft 6 is driven and lowered, the conveyer belts 10 will be driven in a like direction by the mechanism described, the buckets 11 will pick up the dirt dug up by the bit 7 and carry it upwardly where it may be delivered by the buckets into a single chute 37, shown in Fig. 1, and which is secured to the head 5. By driving the belts 10 in the same direction but one chute is needed to receive the discharged dirt. By having the axes of the sprockets 9 in the same plane as the drill shaft 6, the belts 25 may be carried farther into the hole made by the bit 7, than would be the case if the shafts 8 were at one side of the plane of the drill shaft.

The manner of placing the tubular linings, one of which is shown in Fig. 5 and designated by 38, is fully described in the application aforesaid.

I do not limit my invention to the specific structure shown and described, as modifications, within the scope of the appended claims, may be made without departing from the spirit of my invention.

Having thus described my invention, what I claim and desire to secure by Letters Patent, is:—

1. In an earth auger, a drill shaft, two sprockets disposed at opposite sides of the drill shaft and having their axes located in a plane which longitudinally bisects the drill shaft, two conveyer belts respectively driven by said sprockets, a gear wheel having spur teeth and internal teeth, means actuated respectively by said spur and internal teeth for driving said belts in a like direction, and means for actuating said gear wheel and simultaneously actuating said drill shaft.

2. In an earth auger, a drill shaft, two sprockets disposed at opposite sides of said drill shaft and having their axes in a plane which longitudinally bisects the drill shaft, two conveyer belts respectively driven by said sprockets, a gear wheel having spur and internal teeth, two pinions respectively meshing with said two sets of teeth, means respectively actuated by said two pinions for driving said belts in a like direction, and means for actuating the drill shaft and driving said gear wheel.

65 3. In an earth auger, a drill shaft, two

sprockets disposed at opposite sides of said drill shaft, two conveyer belts respectively driven by said sprockets, a gear wheel having two sets of teeth disposed internally and externally respectively, two pinions respectively meshing with said two sets of teeth, means for simultaneously actuating the drill shaft and driving the gear wheel, and means by which said pinions respectively drive said sprockets.

4. In an earth auger, a drill shaft, two conveyer belts disposed at opposite sides of said drill shaft, a gear wheel having two sets of teeth disposed internally and externally respectively two pinions respectively meshing with said two sets of teeth, means actuated by said pinions respectively for respectively driving said conveyer belts, and means for simultaneously actuating the drill shaft and driving said gear wheel.

5. In an earth auger, a drill shaft, two conveyer belts disposed at opposite sides of said drill shaft, a gear wheel having two sets of teeth disposed internally and externally respectively, two pinions respectively meshing with said two sets of teeth, means actuated by said pinions for simultaneously driving said two conveyer belts in a like direction, and means for simultaneously actuating the drill shaft and driving said gear wheel.

6. In an earth auger, a drill shaft, two sprockets, two horizontal shafts secured respectively to said sprockets, two conveyer belts respectively driven by said sprockets, a gear wheel having two sets of teeth disposed internally and externally respectively, two pinions respectively meshing with said two sets of teeth, means actuated by said pinions for respectively driving said horizontal shafts simultaneously, and means for actuating the drill shaft and simultaneously driving said gear wheel.

7. In an earth auger, a drill shaft, two horizontal shafts disposed at opposite sides of the drill shaft and having their axes located in a plane which bisects the drill shaft longitudinally, two sprockets respectively secured to said horizontal shafts, two conveyer belts respectively driven by said sprockets, a gear wheel having two sets of teeth disposed internally and externally respectively, two pinions respectively meshing with said two sets of teeth, means actuated by said pinions for respectively driving said horizontal shafts in a like direction, and means for actuating the drill shaft and simultaneously driving said gear wheel.

8. In an earth auger, a drill shaft, two horizontal shafts disposed at opposite sides of said drill shaft with their axes in a plane which longitudinally bisects the drill shaft, two sprockets secured to said horizontal shafts respectively, two conveyer belts respectively driven by said sprockets, a gear

wheel having two sets of teeth disposed internally and externally respectively, two pinions respectively meshing with said two sets of teeth, means actuated by said pinions for respectively driving said horizontal shafts, and means for actuating the drill shaft and simultaneously driving said gear wheel.

In testimony whereof I have signed my name to this specification in the presence 10 of two subscribing witnesses.

DAVID WILSON.
